UNITED STATES PATENT OFFICE.

HARRY S. FREEMAN, OF DETROIT, AND FREDRICK ZENKER, OF HIGHLAND PARK, MICHIGAN, ASSIGNORS TO SQUARE D COMPANY, OF DETROIT, MICHIGAN, A CORPORATION OF MICHIGAN.

ELECTRIC SWITCH.

1,400,280.

Specification of Letters Patent. Patented Dec. 13, 1921.

Application filed October 25, 1917. Serial No. 198,382.

To all whom it may concern:

Be it known that we, HARRY S. FREEMAN, a citizen of the United States, residing at Detroit, in the county of Wayne and State of Michigan, and FREDRICK ZENKER, a subject of the Emperor of Germany, residing at Highland Park, county of Wayne, and State of Michigan, have invented certain new and useful Improvements in Electric Switches, of which the following is a specification.

This invention relates to electric fuse-holding switches and it has for one of its important objects to provide a compact, durable and inexpensive mechanism adapted to detachably carry a fuse and control an electric circuit.

Another object of our invention is to provide a fuse-holding switch that may be readily assembled from parts substantially all of which are of standard construction. As such parts may be produced by the usual machinery, they are cheaper than the special parts which have been formerly used. It is, therefore, an object of the invention to eliminate as many special parts as possible and to limit the switch to a size which is, as nearly as possible, dictated solely by the size of the fuse which is to be carried.

Another object of the invention resides in the provision of improved means whereby the fuse may be quickly and conveniently attached, positioned and detached.

Still another object of the invention resides in the construction and positioning of the various switch contacts whereby a compact assembly is obtained.

Other objects will be in part obvious and in part pointed out hereinafter.

While our invention may take form in many different embodiments, we will describe in detail one of these embodiments showing a construction having one convenient arrangement of parts and combination of elements for making up the switch. The scope of our invention is, however, to be limited solely by the claims and the prior state of the art.

In the accompanying drawing wherein is shown one of the various possible embodiments of the invention.—

Figure 1 is a view in side elevation of a switch comprising features of the invention.

Fig. 2 is a view in section taken on the line 55 2—2 of Fig. 1, and

Fig. 3 is a view in section taken on the line 3—3 of Fig. 1.

Referring now more particularly to the drawing, there is indicated at 1 a base block of insulation, having mounted thereon in 60 relatively spaced relation a set of standard clip contacts 2 and 3. In the particular form shown the contact 2 comprises a flat attaching portion 4, upstanding side walls 5, bowed inwardly as at 6 and continuing in 65 the form of spaced substantially parallel jaws 7, and the contact 3 comprises a flat attaching portion 8, substantially parallel upstanding walls 9, bowed inwardly and downwardly as at 10 to form spaced compression 70 jaws 11. Both of the contacts 2 and 3 are adapted to be connected to terminals by means of flat conductor strips 12. Screws 13 and 14 pass through the base block 1 and tap into each of these conductor strips, thereby securing said strip and its communicating contact together, and to the base 1. A binding nut 15 is provided for securing the terminal in electrical communication with the conductor strip. 80

Mounted for pivotal movement relatively to the base 1 is a bridging element or carrier 20 of insulating material. This carrier is provided with two fixed angle members 21 and 22 of flat conducting material. The 85 member 21 has an arm or blade 23 secured to the carrier and an arm or blade 24 adapted to fit between the walls or jaws 7 of the clip contact 2. The blade 24 is apertured as at 25 to receive the shank of a pivot bolt 26 90 which passes through the jaws 7 and blade 21 and which is provided with spring washers 27 adapted to bear upon the outer surface of the jaws 7 and react against the head of the bolt 26 and its co-operating nut 30, 95 the nut being adjustable to increase or relieve the tension exerted by these washers.

The angle member 22 has a blade or arm 31 providing its area of attachment to the carrier 20, and a blade or arm 32 adapted to 100 be moved, by movement of the carrier, into and out of position between the spaced compression jaws 11, the latter being formed to exert suitable compression to obtain the desirable electrical and retaining connection. 105

From a consideration of the structure so far described, it will be obvious that contacts 2 and 3 may be mechanically bridged by a pivotal movement of the carrier or bridging element 20 upon its pivot stud 26. 110

The bridging element, however, in the embodiment shown, being constructed of insulating material, no electrical communication between the contacts 2 and 3 is provided by this mechanical bridging. To the end, therefore, of providing electrical connection between these contacts a standard clip contact 40 is mounted in electrical communication with the angle member 21 and is secured thereto, and to the carrier 20, by means of a screw 41 passing through the carrier, the angle member and attaching portions 42 of the contact and tapped into a square nut 43, the latter being positioned between side walls 44 of the contact 40. In the form shown these side walls 44 are bowed inwardly as at 45 terminating in substantially parallel compression walls 46 having lips 47 at their extremities. The contact clip construction just described is duplicated in electrical communication with the angle member 22 as indicated at 50, this contact being secured to the carrier by a screw 51. For convenience, the contacts 40 and 50 may be termed "the fuse-holding contacts" whereas the four remaining contacts comprising clips 2 and 3 and angle members 21 and 22 may be termed "the circuit-controlling contacts."

In each of the contacts 40 and 51 where one of the side walls 44 meets one of the jaws, a piece is struck inwardly as at 52, to serve as a limiting stop for the fuse knife-blade terminals and facilitate the correct positioning of the fuse relatively to the fuse-holding contacts. The conductor 12 at the end of the base opposite the pivotal connection is provided with an upturned lip 53 against which the end of the blade 32 will bring up in the pivotal movement of the carrier to closed circuit position.

The fuse in the form shown is indicated generally as at 60 and is provided with metal end clips 61 and flattened knife-blade terminals 62 and 63 which connect in the usual way with the fusible link within the inclosure 64.

With the parts as in Fig. 1 an electrical circuit is completed from terminal to terminal through conductor 12, contact 2, angle member 21, clip contact 40, fuse 60, clip contact 50, angle member 22, contact 3 and opposite conductor 12. Should the fuse "blow,"

an operator could move the carrier into open circuit position by means of the operating handle 65, thereby mechanically unbridging the contacts 2 and 3. This movement might be continued about the pivot 26 until the fuse became easily accessible, whereupon the operator could withdraw the blown fuse, substitute a new one by inserting the knife-blade terminals thereof between the lips of the fuse-holding clip contacts and move the fuse inwardly between the jaws of these contacts until further movement was prevented by the limiting stops 52. The operator could then move the carrier in the opposite direction causing reengagement of the contact 32 with the walls or jaws 11 of the contact 3, whereupon the electrical circuit is reestablished between the terminals.

Attention is directed to the fact that in the form shown the pivot is independent of either of the fuse-holding clips; that the fuse itself has no part in establishing the pivotal relation between the contacts 2 and 21 and that the fuse-holding clip contacts are not called upon to take part mechanically in the circuit-completing action. These fuse-holding clip contacts are laterally offset relatively to the contacts which coöperate to complete and interrupt the circuit.

As many changes could be made in the above construction and as many apparently widely different embodiments of the invention could be made without departing from the scope thereof, it is intended that all matter set forth in the foregoing description or shown in the accompanying drawings shall be interpreted as illustrative and not in a limiting sense.

What is claimed is:—

A switch comprising contact members mounted on a base plate, an insulating bridging member pivotally mounted on one of said contact members, L-shaped members attached to said bridging member, one leg of each of said L-shaped members being in engagement with said contacts in one position of the bridging member, and clip members adapted to receive a flattened member attached to the other leg of said L-shaped member.

HARRY S. FREEMAN.
FREDRICK ZENKER.
